United States Patent Office.

W. B. GUERNSEY, OF NEW YORK, N. Y.

Letters Patent No. 79,113, dated June 23, 1868.

IMPROVED BOX.

The Schedule referred to in these Letters Patent and making part of the same.

TO ALL WHOM IT MAY CONCERN:

Be it known that I, W. B. GUERNSEY, of the city, county, and State of New York, have invented certain new and useful Improvements in Wooden Boxes; and I do hereby declare that the following is a full, clear, and exact description of the same, reference being had to the accompanying drawings, making a portion of this specification, in which—

Figure 1 is a vertical transverse section of a box complete, made according to my invention.

Figure 2 is a horizontal section of the same.

Similar letters of reference indicate corresponding parts in both figures.

This invention relates to that variety of boxes, the cylindrical sides of which are composed of one or more thicknesses of thin wooden strips or veneering, and which, as hitherto made, have been open to the objection that such sides have been very liable to warp out of shape, and become detached from the bottom of the box. This invention is designed to obviate this defect; and it consists in fitting and cementing the edges of the sides of the box and cover in perpendicular grooves formed annular or otherwise in the bottom and top thereof, whereby such edges are so firmly held in place that the desired object is effectually accomplished.

To enable others to understand the nature and construction of my invention, I will proceed to describe it with reference to the drawings.

In each of the figures, the boxes are represented as complete, that is, composed of two separate boxes, identical in construction, one being slipped or placed over or upon the other to constitute the cover of the same, as shown more fully in fig. 1; each of the two being made in the same manner, except that one is necessarily somewhat larger than the other. A description of one will suffice for both.

Provided in the upper surface of the bottom, A, at a suitable distance from the periphery thereof, is a groove, a' , which may be of any appropriate depth, and of a width corresponding to the thickness of the cylindrical sides B of the boxes, which are formed of one or more thicknesses, $e f$, of thin stuff or veneering. When made of two or more thicknesses, they are glued or cemented together, the two ends of each thickness being brought square against each other, so that a smooth and unbroken surface is secured thereto; the two thicknesses breaking joints in the manner shown in fig. 2, so that one may hold the other in the requisite cylindrical form. The lower edge of the cylindrical sides, previous to its attachment to the bottom, is dipped into glue or other suitable cementing-material, and is then fitted into the groove a' in the bottom, and is thus securely fixed therein, inasmuch as the edge is held upon both its inner and its outer sides by the material of the bottom; it follows that any displacement of the same, from warping or like causes, is effectually prevented.

When the box is to be employed for holding butter or like substances, it is preferred to have the sides thereof composed of two thicknesses of material, as hereinbefore fully set forth; but in some cases, as, for instance, in boxes designed for holding paper collars, the sides may consist only of a single thickness fitted to the bottom of the box in the same manner.

Having thus described my invention, I do not claim the annular groove formed as described in patent No. 63,280; but

What I claim as my invention, and desire to secure by Letters Patent, is—

The improved box, made of veneer, with its sides fitted and cemented into perpendicular grooves in the heads thereof, as a new article of manufacture.
